RAILWAY CROSSING OR LIKE TRACK
STRUCTURE

Eugene W. Caruthers, Secane, Pa.

Application November 7, 1933, Serial No. 696,995

12 Claims. (Cl. 246—460)

This invention relates to crossings, frogs, or other like track structures used at rail intersections, and is applicable to both the solid one piece type of structure and to the composite type wherein rolled rails and steel alloy inserts are fitted together.

Heretofore for special track structures of this nature it has been customary to employ bodies of manganese steel or other steel alloy, and difficulties have been experienced in properly heat treating such bodies to obtain the desired hardness and uniform wear resisting properties. The foundry problem has been to produce a body having walls which are thin enough and of substantially uniform section so that incident to heat treatment the entire body may be uniformly and effectively cooled by the quenching medium, and at the same time to produce a structure having sufficient strength to withstand the severe shocks placed upon it by passing wheel loads.

The object of the present invention is to overcome the aforementioned difficulties, and this end I have accomplished by the provision of a track structure which, departing from the customary practice, utilizes for its main support vertical columns placed beneath the points of application of the wheel loads, such columns serving in effect as continuations of the webs of the adjoining running rails. The track structure of this invention is, in some instances, further characterized by railbound side edges formed to fit the rails but having openings therein which together with the interior of the metal body form passages for the free circulation of a quenching medium throughout the interior of the body.

Other objects and advantages characterizing my present invention will become more fully apparent from the description hereinafter set forth of one embodiment or example thereof, having reference to the accompanying drawings. Of the drawings:

Fig. I represents part of a rail crossing including a special track structure of my invention.

Fig. II represents an enlarged cross-section of the same, taken as indicated by the lines II—II of Fig. I.

Fig. III represents an enlarged cross-section of the same, taken as indicated by the lines III—III of Fig. I.

Fig. IV represents an enlarged cross-section of the same, taken as indicated by the lines IV—IV of Fig. I.

Fig. V represents an enlarged vertical cross-section of the central insert, taken as indicated by the lines V—V of Fig. I; and,

Fig. VI represents a horizontal cross-section of the central insert, taken as indicated by the lines VI—VI of Fig. V.

With particular reference to Fig. I, there is shown a composite crossing frog of my invention comprising generally a central metal insert 1 joined to running rails 2, 3, 4 and 5, and guard rails 6, 7. Preferably the metal insert 1 is constructed of manganese steel or like steel alloy and has at each end thereof a pair of diverging arms, one such pair being designated at 8 and the other such pair being designated at 9. In the particular example shown, certain of the running rails, namely those designated at 4 and 5 terminate abruptly at their juncture with the metal insert 1, whereas other running rails, those designated at 2 and 3 are bent around the sides of the insert 1 and terminate in projecting ends 10, 11 which serve as guards for the running rails 4, 5, respectively.

The metal insert 1 is made of one piece, and as clearly shown in the cross sectional views represented in Figs. II to V, is of hollow box-like construction. The head portion 12 has thereon intersecting flangeways 13, 14 and adjacent to 25 the flange-ways 13, 14 there are tread surfaces 15, 16, respectively, the tread surfaces 15, 16 forming continuations of the tread surfaces of the adjoining running rails 2, 3, 4 and 5. Beneath the gage sides of the tread surfaces 15, 16 of the insert 1, there are provided intersecting vertical columns 18 which join the head portion 12 to the base portion 20 and afford the main support for the insert. The disposition of the intersecting vertical columns 18 is clearly shown in Fig. VI, and it will be seen that these columns form in effect continuations of the webs of the adjoining running rails 2, 3, 4 and 5, and serve to support the head portion 12 of the insert substantially at the points of application of passing wheel loads.

The side edges of the head and base of the inserts 1, as most clearly shown in Fig. II, are formed to a shape complementary to the adjacent rails and are fitted thereto with the parts joined together by one or more through bolts 22. At the 45 sides of the insert 1, openings 23 are provided. Such openings 23 may vary in number and size; and depending upon the angle of intersection, one or more struts 24 may be utilized to give additional support to the head portion 12 at its side edges. The openings 23 form with the interior of the metal body 1 unobstructed passages for the free flow of a quenching medium used during the process of heat treatment. Like openings 25 are provided at each end of the metal insert 1, and 55

these openings 25, together with additional openings 26 formed in the base portion 20 of the insert 1, and the bolt-hole openings 28, form passages which permit the quenching medium to flow freely through all portions of the metal body.

5 In the particular example illustrated, the diverging arms 8, 9 of the metal insert 1 are fitted to the adjoining running rails and guard rails in the manner shown in Figs. III and IV. At 10 these points the running rails and guard rails are spaced apart by flangeway fillers 27 and are joined together by bolts 28. Desirably lock washers 30 and head lock washer plates 31 are associated with the bolts 28 and with the central body bolts 22.

15 As shown in Figs. V and VI, the intersecting vertical columns 18 are provided with bolt holes 29, through which the bolts 22 pass; and such bolt holes aid considerably in the circulation of 20 the quenching medium through the interior of the body 1 without materially lessening the strength of the columns.

25 From the above description it will be apparent that the metal insert 1 of this invention is assembled rigidly with the adjoining rails and is given extra strength at the regions where such strength is particularly desired by the provision of the vertical columns 18 which are disposed substantially beneath the tread surfaces 15, 16 30 and in approximate alignment therewith. The columns 18 extend completely across the insert and abut against the running rails. Moreover, while the metal insert 1 is thus amply rigid and adequately supported at the critical regions 35 thereof, the head portion of the insert is desirably of relatively thin cross section and of substantially uniform thickness throughout. It will be observed that the formation of the inserts as described provides in the interior thereof a number of passages which are unobstructed to allow a quenching medium to pass freely through the body with a uniform cooling effect upon the exposed surfaces. There are no cavities or dead spaces on which such circulation is retarded.

40 Accordingly, the track structure of my invention combines the qualities of strength and economy in method of manufacture, as well as satisfying the conditions necessary for the heat treatment of the metal body to obtain the desired 45 shock and wear resisting properties.

50 While I have described my invention with respect to one embodiment or example thereof applied to a particular form of track structure, it will be apparent that the invention is applicable to many different types of track structures and that changes in the form of the structure may be made without departing from the spirit of the invention as defined in the annexed claims. More 55 particularly, it will be apparent that the invention may be applied to both solid and built-up types of special track structures, and that the disposition and form of the supporting vertical columns and the number, size and location of the 60 openings leading to the interior of the body will vary according to the type of structure desired and the angle of intersection of the rails.

65 Having thus described my invention, I claim:

1. In a railway crossing or like track structure, 70 a metal body having a head portion with tread surfaces and crossing flangeways thereon, a base portion, and crossing vertical columns joining said head and base portions beneath the gage sides of the tread surfaces, said metal body having side edges of a shape complementary to a 75 rail section and having openings at the sides

forming with the interior of the body circulatory passages to permit the free flow of a quenching medium throughout the central portion of the body.

2. In a railway crossing or like track structure, 5 a metal body having a head portion with tread surfaces and crossing flangeways thereon, a base portion, and perforated vertical crossing columns joining said head and base portions beneath the gage sides of the tread surfaces, said metal body 10 having openings at the sides thereof forming with the interior of the body and with the perforations in the vertical columns circulatory passages permitting the free flow of a quenching medium through all parts of the body. 15

3. A railway crossing or like track structure of the composite type comprising rails and a hollow metal insert joined thereto, said insert having aligned tread surfaces and crossing flangeways at the head portion thereof, and vertical 20 crossing columns beneath the gage sides of said tread surfaces, and coextensive therewith, and having openings at the sides adjacent to the rails.

4. A railway crossing or like track structure 25 of the composite type comprising rails and a hollow metal insert joined thereto, said insert having aligned tread surfaces and crossing flangeways at the head portion thereof and having its head and base portions joined by crossing 30 vertical columns disposed beneath the wheel contacting portions of the tread surfaces, and said insert having openings at the sides adjacent to the rails serving as passages for a quenching medium when the insert is heat treated. 35

5. A railway crossing or like track structure of the composite type comprising rails and a hollow metal insert joined thereto, said insert having aligned tread surfaces and crossing flangeways at the head portion thereof and having 40 vertical crossing columns directly beneath and in substantial alignment with the wheel contacting portions of said tread surfaces, and said insert having side edges conforming to the contour of the adjacent rails with openings at the 45 sides serving as passages for a quenching medium when the insert is heat treated.

6. A railway crossing or like track structure of the composite type comprising rails and a hollow metal insert fitted thereto, said insert including a head portion having tread surfaces and crossing flangeways thereon, a base portion, and crossing vertical columns joining said head and base portions beneath the wheel contacting portions of the tread surfaces, and said insert having side edges conforming to the contour of the adjacent rails and having a plurality of openings at the sides thereof serving as passages for a quenching medium leading to the central portion of said insert, and the ends and base portion of said insert having additional such openings. 55

7. A railway crossing or like track structure of the composite type comprising rails and a hollow metal insert joined thereto, said insert having intersecting tread surfaces and flangeways at the head portion thereof and having openings at the sides and ends thereof, and intersecting vertical columns extending beneath the flangeways near their point of intersection and joining the head and base portions of the insert 70 beneath the gage sides of the tread surfaces, said columns being coextensive with said tread surfaces and forming substantially continuations of the webs of the running rails. 75

8. A railway crossing or like track structure

- of the composite type comprising rails and a metal insert bolted thereto, said insert having intersecting tread surfaces at the head portion thereof, and having intersecting vertical columns 5 extending beneath said tread surfaces and perforated with bolt holes in the central portion of the insert, and having openings at the sides adjacent to the rails which together with the bolt holes aforesaid form with the interior of the 10 insert passages permitting the free flow of a quenching medium through all parts of the insert.
9. In a railway crossing or like track structure, a metal body having a head portion with aligned 15 tread surfaces and crossing flangeways adjacent to said tread surfaces, a base portion, and crossing vertical columns joining said head and base portions beneath the gage sides of the tread surfaces and coextensive therewith, said metal body 20 having a series of openings forming with the interior of the body circulatory passages permitting the free flow of a quenching medium throughout the central portion of the body.
10. In a railway crossing or like track structure, a metal body having a head portion with aligned tread surfaces and crossing flangeways adjacent to said tread surfaces, a base portion, and crossing vertical columns joining said head and base portions beneath the gage sides of the 25 tread surfaces and coextensive therewith, said metal body having openings at the ends and in the base portion near the ends, and having a plurality of openings at each side, the aforesaid 30
- openings forming with the interior of the body circulatory passages permitting the free flow of a quenching medium throughout the central and end portions of the body.
11. In a railway crossing or like track structure, a metal body having a head portion with aligned tread surfaces and crossing flangeways adjacent thereto, a base portion, and crossing vertical columns joining said head and base portions beneath the gage sides of the tread surfaces, said columns extending beneath the flangeways near their point of intersection, and said metal body having a series of openings forming with the interior thereof passages permitting the free flow of a quenching medium through the 15
12. In a railway crossing or like track structure, a metal body having a head portion with aligned tread surfaces and crossing flangeways adjacent to said tread surfaces, a base portion, 20 and crossing vertical columns joining said head and base portions beneath the gage sides of the tread surfaces and coextensive therewith, said metal body having a series of openings forming with the interior of the body circulatory passages 25 permitting the free flow of a quenching medium throughout the central portion of the body, said openings including openings in said vertical columns and in the base portion of the crossings, all of which are disposed adjacent to the intersection.

EUGENE W. CARUTHERS.
